UNITED STATES PATENT OFFICE.

JOHN BRANDWOOD, OF BIRKDALE, SOUTHPORT, AND THOMAS BRANDWOOD, OF ELTON,
BURY, ENGLAND.

COLLAPSIBLE SPINDLE FOR THE DYEING AND ANALOGOUS TREATMENT OF WOUND YARNS.

Application filed December 19, 1928, Serial No. 327,150, and in Great Britain July 28, 1927.

This invention relates to spindles on which 5
yarn packages in wound form, and which
will be hereinafter referred to as yarn
cheeses, are mounted for the dyeing or anal-
ogous treatment of the cheeses by passing
fluid under pressure therethrough. Spindles
consisting of tubes having a cylindrical per-
forated surface for this purpose are known,
but with many kinds of yarn—notably linen
10—the said yarn contracts so much on being
wetted that it is impossible to take the con-
stricted cheese from the tube or spindle.

It is the object of this invention to provide
means whereby cheeses may be easily slipped
15 upon a spindle having a perforated surface
and be easily removed therefrom after fluid
treatment, no matter how great the con-
striction of the cheeses which may have oc-
curred. A further object is to make these
20 means of such a strong and simple construc-
tion that the spindle will not be easily dam-
aged or knocked out of order by rough han-
dling in the dyehouse or other place where
it is used.

25 According to the invention the collapsi-
ble spindle is composed of a plurality of
perforated sections which form the surface
of the spindle each such section being move-
able radially of the spindle center; a fixed
30 central rod; and a sleeve slidable upon the
said rod which sleeve is connected by links
to each such perforated section; and links
which act as distance pieces between the
fixed central rod and each such section.

35 Sliding movement of the sleeve upon the
rod will thus, through the medium of the
link connection between the said sleeve and
the sections, cause the latter to move in-
wardly or outwardly, and the distance
40 pieces, consisting of links will vary their
angle to ensure that at all relative positions
of the perforated sections and the fixed cen-
tral rod they will be effective for their pur-
pose, and cause each section to move evenly
45 radially as a whole. In its expanded or con-
tracted position therefore the spindle will
be of the same diameter throughout its
length.

Four perforated sections are found very
50 convenient in practice, the longitudinal
edges of two diametrically opposed pairs
slightly overlapping the adjacent edges of
the other two diametrically opposed sec-
tions, and to operate controllably the sliding

sleeve, a nut threaded upon the fixed cen- 55
tral rod and engaging the sleeve by a collar
rotatable with the nut is found convenient
and simple.

The invention with arrangement of de-
tails in a very convenient and practical 60
form will now be fully described, reference
being had to the accompanying drawings
wherein:—

Figure 1 is a cross section partly in ele-
vation of a spindle constructed according to 65
the invention;

Figure 2 is a longitudinal section taken
on line 2—2 of Figure 1;

Figure 3 is a cross section taken on line
3—3 of Figure 1; and

Figure 4 is a bottom view of the spindle
showing the manner in which it is fitted to
seat the said spindle for use in a machine
for dyeing or analogous fluid treatment.

Referring to the drawings, the surface of 75
the spindle is composed of four perforated
sections 5, 6, 7 and 8 the longitudinal edges
of the sections 5 and 7 slightly overlapping
the adjacent edges of the sections 6 and 8
as clearly seen in Figures 2 and 3. The base 80
of the spindle is formed by a cylindrical
member 9 and at the lower end of the said
member spokes 10 are provided with a cen-
tral hub or boss 11 into which is secured by
the nut 12 the extremity of a rod 13 which 85
forms the fixed central rod of the spindle
and extends above the upper edges of the
sections 5, 6, 7 and 8. This rod is of round
section where threaded to engage with the
nut 12, of rectangular cross section up to 90
the point 14 of Figure 1 and from that point
to its top is again of round section, part of
which section is threaded.

Upon the smooth round section at the up-
per part of the rod is slidably fitted a sleeve 95
15 having at its lower portion the radial
projecting member 16 and the said sleeve is
recessed and undercut as shown at 17 to
receive rotatably therein a collar 18 which
fits rotatably upon the rod 13 and is formed 100
solid with a nut 19 placed upon the thread
on the spindle so that the nut may be turned
to move in either direction longitudinally
of the said rod. Each of the perforated sec-
tions 5, 6, 7 and 8 has fitted longitudinally 105
and centrally thereof a stiffening member
20 which may conveniently be of channel
section as seen in Figures 2 and 3 and to the

upper end of each such stiffening member is pivoted by means of a pivot pin 21 a pair of links 22 the other ends of which are pivoted to a radial projection 16 on the 5 sleeve 15. Right or left hand manipulation of the nut 19 will therefore cause the link pairs 22 to vary their angle to the vertical and thus exert a pull or a push upon all the perforated sections 5, 6, 7 and 8 to move 10 them radially inwardly or outwardly.

At intervals through their lengths each stiffening member 20 has linked thereto as shown at 23 the link pairs 24 the other end of each link being pivoted to a pivot pin 15 25 passing through the fixed central rod 13. These link pairs 24 are in staggered relation as seen in Figure 1 and they act as distance pieces between the central rod 13 and the particular section 5, 6, 7 or 8 to 20 which they are linked. As will be seen, the sections 5, 6, 7 and 8 being prevented by the controlled sleeve 15 and the link pairs 22 from moving longitudinally of the fixed central rod 13 the link pairs 24 will act effectively as distance pieces at all radial positions of these sections and at all variations to the horizontal of the angle of the said linked pairs 22.

As in a treatment spindle of this character 30 it is essential that fluid shall pass only through the perforations of the surface and through the material mounted thereon, the spindle is closed at its upper end when in operation by a removable cap. Such a cap 35 is shown in Figure 1, being of dished form at 26 and having a flange 27 which fits upon a packing ring 28 placed on the top of the cheeses *y* upon the spindle. The upper extremity of the fixed central rod 13 is formed 40 as a threaded neck, upon which the cap, having a tapped central hole to correspond, may be screwed, a wing nut 29 holding it in this position. The spindle is thus open only at the bottom fluid gaining ingress or 45 egress between the spokes 10 of Figure 4, to the spindle, and through the material on the spindle and the perforations in the surface thereof.

In operation, when cheeses are to be placed 50 upon the spindle the latter is first contracted, by turning the nut 19 so that it moves upwardly on the central rod 13 thus drawing upwardly the sleeve 15. The connected links 22 thus draw the sections 5, 6, 7 and 55 8 inwardly, adjacent edges thereof sliding over adjacent edges of other section, the distancing links 24 assuming an angle to the horizontal and each such section moving evenly and as a whole.

60 The spindle being thus contracted, cheeses *y* are easily mounted thereon, the bore of the cheeses being of greater diameter than the now contracted spindle. This operation of charging the cheeses upon the spindle 65 with the bottom collar or ring 30 similar

rings interposed between the cheeses, and a top closer 28, may all be as described in our prior United States Letters Patent No. 1,454,312.

The cheeses being mounted on the spindle, 70 the nut 19 is now again rotated but in the reverse direction, and the sleeve 15 descends, thus by means of the links 22 forcing the sections 5, 6, 7 and 8 outwardly, the distancing links 24 following this movement. The 75 cheeses being now tight upon the spindle as a result of the expansion of the latter, pressing of the charge of cheeses as described in our prior United States Letters Patent No. 1,454,312 may take place and when sufficiently pressed the cap 26 may be placed in position as described, and as seen in the drawing, Figure 1. The spindle may then be screwed into a plate in the treatment apparatus and fluid under pressure passed 80 through the bottom of the spindle, through the perforations in the surface and through the cheeses, this flow of fluid being reversed as desired, all as described in our prior United States Letters Patent No. 1,454,312. 90

To remove the cheeses from the spindle after completion of the desired treatment, the cap 26 is removed and the nut 19 is again turned but in the reverse direction so that it, and the attached sleeve 15 ascend, thus 95 through the medium of the link pairs 22 drawing the sections 5, 6, 7 and 8 inwardly. The distancing link pairs 24 follow this movement, each section 5, 6, 7 and 8 thus moving evenly. The cheeses even in their contracted condition due to the treatment to 100 which they have been subjected, for instance, with dye liquor are now again loose on the spindle and may be easily removed for further handling.

The sections 5, 6, 7 and 8 are of a non-corrodible metal or alloy for instance nickel or nickel alloy, and the other parts may be of any non-corrodible metal, or be coated with any such metal or with any anti-corrosion coating to prevent corrosion or the free movement thereof where movement is essential to the manipulation of the spindle. 105

We claim:

1. A spindle having a perforated surface composed of a plurality of parts arcuate in cross section and movable radially to the spindle center, a fixed central rod, a collar 115 slidable upon the central rod and connected to the perforated parts by links, and further links acting as distance pieces between each such part and the fixed central rod. 120

2. A spindle as claimed in claim 1, the perforated surface consisting of four parts arcuate in cross section, the longitudinal edges of two diametrically opposed sections overlapping the adjacent longitudinal edges of the other two diametrically opposed sections. 125

3. A spindle as claimed in claim 1, the 130

slidable collar upon the central rod being slidably operated by a nut threaded upon the fixed central rod and engaging by a collar rotatably held by the sliding sleeve.

- 5 4. A spindle as claimed in claim 1, the links acting as distance pieces being pivoted to the fixed central rod and to a strengthening and supporting rod fixed longitudinally and centrally of each perforated section.
- 10 5. A spindle as claimed in claim 1, the lower edges of the perforated sections being movable in a recessed base and radially to the said recess.
- 15 6. A spindle as claimed in claim 1, and having also a base provided with a recess in which the lower portions of the perforated

sections are movable radially, the said base being provided with spokes and a central hub into which the fixed central rod of the spindle is screwed.

20

7. In combination with a spindle as claimed in claim 1, a closer cap adapted to screw upon the upper extremity of the fixed central rod of the spindle to close such upper end when the material to be treated has been 25 charged upon the spindle and the sections of the latter expanded substantially as set forth.

In testimony whereof we have hereunto set our hands.

JOHN BRANDWOOD.

THOMAS BRANDWOOD.
